APPARATUS FOR DETERMINING THE
INCLINATION OF WELL HOLESClaude E. Leach, Los Angeles, Calif., assignor, by
mesne assignments, to Alexander Anderson,
Fullerton, Calif.Application April 29, 1929, Serial No. 359,001
Renewed February 6, 1933

2 Claims. (Cl. 234—1)

My invention pertains to apparatus for determining the inclination of well holes.

My apparatus is utilized in drilling deep well holes such as for oil well drilling, in which it is desired to ascertain if the hole is being bored from the true vertical and the amount of the inclination.

In one of the forms of the procedure it has been the practice to lower a glass container or the like having hydrofluoric acid therein, to a preselected level at which inclination is to be determined and after allowing the container to rest at that level for a short time to remove it to the surface. The hydrofluoric acid reacts on the glass giving an etching and the inclination of the surface of this etching is used to determine the inclination of the bore of the well as the surface of the acid assumes a horizontal position. In the prior practice the container having the hydrofluoric acid has been lowered by means of drill pipe, that is when the drill pipe is lowered or by a cable or a bailer, but this is a slow procedure and the acid reacts on the glass while the container is being lowered.

An object of my invention is to release the container in the well at the top, but in such manner that the container is not broken when it reaches travel arresting means in the well hole and in lowering of the container to be able to determine when the container has reached the arresting means. The container is then left in such position for a predetermined time and then removed to the surface and utilized to determine the inclination of the well by the angle the surface etching takes with the glass.

A further object of my invention is dropping the container in the well through a string of drill pipe and having the container come to a stop at the drill bit. The container after remaining a predetermined time at the bottom is raised to the top by hoisting and uncoupling the string of drill pipes.

A still further object of my invention is dropping a glass container in the well through the slushing fluid or the liquid in the well and preferably through the slushing fluid contained in the string of drill pipe, and in this connection I form the container and its holder of such material and shape that the holder having the container will readily drop through the slushing fluid in the drill pipe but the velocity is reduced by the continuous displacing action of the hydraulic fluid in the more or less narrow clearance between the holder for the container

and the drill pipe and the couplings and joints thereof. This allows the holder with the container to strike the bit without breaking the glass container.

A still further object of my invention is the construction of a free falling holder and means to dampen and arrest the fall of the container so that a resilient action is obtained thereby preventing breaking of the container by the jolt of striking the travel arresting means.

In this connection a more detailed object of my invention is making the holder with a telescopic plunger-like device having a resistant spring and also a chamber for hydraulic fluid which is expelled when the spring is compressed due to the blow in striking the bottom of the drill string. The container itself is supported on a resilient mattress or the like.

A further detailed feature of my invention is forming the holder with a long tubular tail piece which effectively guides this in falling through the drill string and which may be made hollow and by its displacement give a desired degree of buoyancy to the holder and the container, thus causing the device to fall at such a rate of speed that the blow on the bottom will be insufficient to break the container and yet allow the device to drop sufficiently rapidly so that the hydrofluoric acid has but little opportunity to etch the glass in its descent.

My invention is illustrated in the accompanying drawing in which,

Figure 1 is a diagrammatic vertical section of a well much enlarged in diameter;

Fig. 2 is a vertical section through the lower end of a drill collar and drill bit, showing my holder mounted therein;

Fig. 3 is a vertical section through the holder and showing the container;

Fig. 4 is a section on the line 4—4 of Fig. 3 in the direction of the arrows;

Fig. 5 is a modified vertical section showing another type of mounting for the container;

Fig. 6 is a vertical section through the container, showing the manner of etching and illustrating the etching and showing the inclination of the well;

Fig. 7 is a vertical section of a modified stopping arrangement for the container;

Fig. 8 is a detail vertical section showing the container at the top of the holder.

In Fig. 1 the bore of the well is indicated by the numeral 11, the well being illustrated as having a well casing 12 and a string of drill pipe 13, the couplings being indicated at 14. At the bot-

tom of the string there is the usual drill collar 15 and a drill bit 16. This bit is indicated as having a fish tail cutting end 17 and has a socket 18 with slushing ducts 19 leading from the socket 5 to discharge adjacent the bit. With my invention I may utilize any standard type of hydraulic drilling equipment.

My holder structure designated generally by the numeral 20 is elongated and has a plunger 10 section 21 with grooves 22 on opposite sides, the plunger having a head 23 at the end which fits and slides in a vertical chamber 24 formed in the bottom portion 25 of the holder. The bottom portion of the holder is provided with a pilot 15 or tapered end 26 and preferably with a squared end 27. A pair of screw threaded pins 28 extend through the upper end of the bottom portion of the holder above the head 23 and fit in the grooves 22. There are a plurality of apertures 20 29 leading into the bottom of the chamber 24 and a coil spring 30 is also mounted in this chamber bearing against the inside of the point 26 and the lower part of the plunger 21.

The plunger is provided with a container holding section 31 with shoulders 32 immediately therebelow. This section has a deep socket 33 in which is mounted a glass container 34, there being a packing 35 around the container and the container rests on a spring mattress 36 30 at the bottom. The container may have a cork or other plug 37 forming a closure at the top and such container is preferably made cylindrical.

A coupling cap 38 is screw threaded on the 35 upper end of the plunger portion of the structure having the container therein and this has a recess 39 in which is mounted a spring 40 which bears on the top of the plug of the container. A tubular tail piece 41 is threaded to the top of the 40 coupling cap and this may be made quite thin and it is desirable to have a number of partitions or other transverse strengthening members 42 across this tail piece. These if desired may have apertures 43 therethrough also if desired to close 45 this tailpiece with a plug 44. By having this tailpiece of sufficient length and cross sectional interior area I may obtain a displacement which will give a certain buoyancy to the holder considered as a whole and therefore function to 50 reduce the velocity with which the holder having the container will drop through the slushing fluid; this having a greater buoyancy than if the whole structure other than the container is made of solid metal.

55 The manner of operating my device is substantially as follows: When a well is being bored by rotary hydraulic equipment and before the drill string is withdrawn I drop my holder having the container mounted therein and the container having a partial filling of hydrofluoric acid or other etching fluid therein; the slushing fluid is still in the drill string and the device drops to the bottom. The passage of this downward may be readily detected by listening to the 60 holder striking the joints and couplings of the drill string in its drop and the sound made by the striking at the bottom may be readily detected and also the absence of the noise of striking the 65 joints of the drill string notifies the operator that the device is at the bottom of the well.

In striking the bottom of the drill string the 70 spring 30 is compressed by the plunger 21 thrusting downwardly and besides this the hydraulic fluid which falls into the chamber 24 is expelled by the downward moving plunger. This cham-

ber becomes filled with hydraulic fluid as there is sufficient leakage at the head of the plunger to allow the air to escape or this chamber may be filled with water before the device is dropped. This breaks the jolt on the container and the 80 springs 36 and 39 also lessen the breaking action on the container so that I find that my device may be used on very deep wells without the container breaking.

The pilot end 26 facilitates the guiding of the 85 device at the collars and couplings and also its passage through the hydraulic fluid and in addition when it rests on the drill bit the points do not block the slushing ducts so that the slushing action may be continued.

The holder with its container is left at the bottom of the well a more or less predetermined time, giving sufficient time for the acid to react with or etch the glass or the container and as the holder is in parallelism with the elongated axis of the well hole and the surface of the acid is horizontal and libratory in relation to the container, the angle of this surface with respect to the elongate axis of the holder may be utilized to determine the inclination of the well after the 100 drill string is pulled to the surface. The elongate axis or any other datum line or plane serves as a comparative means for the purpose of measuring inclination. While the etching action continues in this upward hoisting of the drill string, nevertheless the surface level is well illustrated with my procedure and especially so as the device drops freely under the action of gravity.

In order to adjust or extend the tail piece 41 I 105 make this in sections having a screw joint 45 so that a plurality of sections can be joined together, thus changing the buoyancy of the construction when immersed in the slushing fluid.

In Fig. 5 I illustrate a modified type of mattress for the container, this being illustrated as 110 having a rubber mattress 46 below the container and a second rubber mattress 47 on top of the container. Also, if desired I may use a rubber mattress instead of the spring 30 in the chamber 24.

115 In some cases I may employ a spring 48 located in the socket in the drill bit so that the point of the holder strikes on this spring. This gives an additional resilient buffer to the stopping of the holder and its container.

120 In Fig. 7 I illustrate a modified construction in which a drill pipe, drill collar or the like 49 has a spider or shoulders 50 constructed therein serving as an arrester and functioning to stop the fall of and support the holder and on this arrester may be mounted a buffer spring 51 so that the tool in dropping strikes this buffer spring and thus aids in stopping the device. Where I use a buffer spring I find that I may dispense with the telescopic action of the holder having no resilient resistance in the holder itself except for the mounting of the container.

125 In Fig. 6 the line 52 illustrates the etching showing the inclination of the surface formed by the hydrofluoric acid in the glass.

In Fig. 8 I illustrate a holder designated generally by the numeral 53. This has a tubular section 54 with the container mounted therein on springs and there is a plug 55 above the container 130 with a spring between the container and the plug. A hollow tubular section 56 having threaded joints is spaced between the upper section of the holder and the plunger section 57. A point similar to that shown in Fig. 3 is utilized in connection with 135

the plunger section having the telescopic action with the buffer spring therein.

Various changes may be made in the principles of my invention without departing from the spirit thereof as set forth in the description, drawing and claims.

I claim:

1. Apparatus for determining the inclination of well holes comprising a free falling elongated holder having a lower end adapted to strike a fall arrester in a well hole, an upper portion of the holder telescoping with the lower portion, a cushioning element to resist said telescoping, a fragile container mounted in the upper portion and having an etching liquid therein, the holder

with the container being adapted to drop by gravity in a well hole and to be lifted to the top of the well hole.

2. Apparatus for determining the inclination of well holes comprising in combination a free falling elongated holder formed in a plurality of sections telescoping together, the lower section being adapted to strike a fall arrester in a well hole, means to resist telescopic action including a spring, a fragile container in the upper section having an etching liquid therein, a resilient mounting for the container, said holder with the container being adapted to drop by gravity in the well hole and to be elevated therefrom.
